UNITED STATES PATENT OFFICE

JULIA M. GRABOWSKI, OF WAUKESHA, WISCONSIN

EYELASH CURLER

Application filed May 13, 1930. Serial No. 452,094.

This invention relates to an improved eyelash curler.

It has been found that if eyelashes are permitted to droop, they soon become unsightly and are sometimes turned inwardly so that their ends often become lodged between the eyelid and the eyeball, thus causing great pain and inconvenience. Furthermore, persons wearing eyeglasses are often annoyed by their eyelashes coming in contact with the lenses of such glasses and, in order to obviate this annoyance they often cut off the end portions of the lashes. This practice results in the lashes becoming coarse.

One object of the present invention is, therefore, to provide an eyelash curler which will effectually curl the eyelashes so that their beauty will be enhanced and annoyance therefrom will be obviated.

Another object of the invention is to provide a device of this character which is so formed that a plurality of lashes may be curled at a single stroke.

A further object of the invention is to provide an eyelash curler which will be efficient in operation and which will be cheap to manufacture.

With these and other objects in view, the invention will be hereinafter described in detail, reference being had to the accompanying drawings wherein:

Figure 1 is a perspective view showing the device upon the index finger of the hand and about to be applied to the eyelashes for a curling operation.

Figure 2 is an enlarged bottom plan view of the device.

Figure 3 is an enlarged longitudinal sectional view on the device on the line 3-3 of Figure 2, looking in the direction indicated by the arrows.

Referring now to the drawings, the numeral 1 indicates the index finger of a human hand and 2 the thumb thereof. A human eye is designated at 3 and a few eyelashes are shown at 4.

My improved eyelash curler comprises a thimble 5 which may be formed of metal or other suitable material and which is pro-

vided with a reinforcing rim 6, said rim tending to prevent accidental crushing or splitting of the thimble and also providing a smooth edge for the mouth of the thimble. The thimble is, of course, closed at one end and is tapered toward said closed end to conform to the outer end portion of the index finger 1.

As seen more clearly in Figure 3 of the drawings, the upper portion of the side wall of the thimble is extended in the same plane past the closed end of said thimble to provide an arcuate curler flange 7. This flange is provided with a curved free edge 8 and rounded receding corners 9 and 10, said edge permitting more firm engagement of the flange with the eyelashes and said rounded corners 9 and 10 obviating danger of scratching the lid or bruising the lashes.

In operation, the thimble 5 is first placed upon the index finger 1 of the hand with the flange 7 disposed at the upper side of said finger; that is, above and forwardly of the nail of said finger. The thumb 2 is then placed under the lashes 4 and the index finger 1 is contracted and moved toward said thumb with the outer end thereof presented at a right angle to the thumb, thus bringing the flange 7 into contact with the lashes directly above the thumb and more or less tightly clamping said lashes between the thumb and said flange. The finger is then further contracted, when the flange will be drawn lengthwise of the lashes, thus curling them upwardly. The lower lashes may, of course, be curled downwardly by placing the flange below the lashes and the thumb at the top thereof and repeating the drawing operation.

Attention is directed to the fact that repeated use of this efficient eyelash curler will not only enhance the beauty of the lashes, but, by stimulating the circulation at the roots of the hair, will also promote the growth of the lashes and thereby maintain them in a healthy condition.

What is claimed is:

1. An eyelash curler including a thimble adapted to receive a finger and having an integral curler flange thereon disposed for curl-

ing an eyelash between said flange and the thumb.

- 5 2. An eyelash curler including a thimble adapted to receive a finger and having a side wall extended at the upper portion of the thimble to form an arcuate curler flange disposed for curling an eyelash between said flange and the thumb, said flange having a curved free edge and rounded corners.
- 10 3. An eyelash curler including a thimble shaped to conform to the end of a finger and having a wall and an integral arcuate curler flange projecting forwardly therefrom in the same plane with said wall, said flange being curved at its free end to conform to the curvature of the thumb and being adapted to engage an eyelash between said finger and thumb for a curling operation.

In testimony whereof I affix my signature.
